TELEVISION SYSTEM

Rudolf Urtel, Berlin, Germany, assignor to Telefunken Gesellschaft fur Drahtlose Telegraphie m. b. H., Berlin, Germany, a corporation of Germany

Application March 26, 1936, Serial No. 70,906.
In Germany March 26, 1935

10 Claims. (Cl. 178—6)

The present invention relates to a method for reporting any occurrences or incidents by way of television, more particularly by the use of cathode ray scanning devices. Such reporting apparatus should be as light as possible, and transportable. Hitherto, this requirement could not be complied with in view of the fact that even by using cathode ray scanning devices, the transmitter arrangements were still rather cumbersome. Moreover, the keeping in step of the transmitter arrangement for instance of the deviation potentials or deviation currents of the cathode ray scanner demands the production of a very exact succession of impulses. The production of this succession of impulses again depends upon the employment or use of a cumbersome and accurate scanning disk.

In accordance with the invention the reporting apparatus having the desired properties can be obtained in the following manner:

The entire arrangement is composed of a main transmitter remote from the place of reporting, and of a reporting apparatus in alternating connection with the main transmitter. The invention will be better understood with reference to the drawing which shows in block diagram an embodiment of my invention.

The synchronizing impulses are produced at the main transmitter 9 in the known manner by means of a local synchronizing means 11 such as a scanning disk or the like, and said impulses are radiated as modulation of the main transmitter. It is hereby immaterial whether a single or multiple channel method is utilized. The main transmitter will be received at the place of reporting such as by the local receiver 7, and the synchronizing impulses are separated from the remaining modulation (picture or sound) in the known manner at 5, and utilized for synchronizing the relaxation arrangement or the like of the image recording apparatus 1. The picture modulation produced by the latter is now sent out by the modulator 3 to the main transmitter across cable or relay transmitter 17.

What I claim is:

1. A television system comprising a main transmitter, means to modulate the transmitter by synchronizing signals, an auxiliary television transmitter, means to receive synchronizing signals from the main transmitter, means to isolate the received synchronizing signals, means to utilize the isolated synchronizing signals for synchronizing the auxiliary transmitter, means to transmit picture signals from the auxiliary transmitter to the main transmitter and means

to modulate the main transmitter by the picture signals transmitted from the auxiliary transmitter.

2. In a television system wherein is provided a main transmitter, and an auxiliary transmitter remote therefrom, the method of transmitting electro-optical representations of a scene from the main transmitter, which comprises the steps of transmitting synchronizing energy from the main transmitter, receiving the synchronizing energy at the auxiliary transmitter, synchronizing the auxiliary transmitter by the received synchronizing energy, transmitting energy representative of the object to be transmitted from the auxiliary transmitter to the main transmitter and modulating the main transmitter by the energy transmitted from the auxiliary transmitter.

3. A television system comprising a main transmitter, means for transmitting synchronizing energy from said transmitter, an auxiliary transmitter, means to receive the transmitted synchronizing energy at the auxiliary transmitter, means to synchronize the auxiliary transmitter by the received synchronizing energy, means to transmit signals representative of an image to be transmitted from the auxiliary transmitter to the main transmitter and means to transmit from the main transmitter energy representative of the signals transmitted by the auxiliary transmitter.

4. The method of television transmission which comprises the steps of generating at a local position synchronizing signals, remotely producing signals representative of an image to be transmitted, synchronizing the remotely produced image signals by the locally generated synchronizing signals, transmitting the remotely produced signals to the local position, receiving the transmitted signals at the local position, and simultaneously transmitting at the local position both the locally generated synchronizing signals and the received remotely produced signals.

5. A television transmitting system comprising means to generate synchronizing signals at a local position, means remote from the local position for producing signals representative of an image to be transmitted, means to synchronize the image signal producing means by the locally generated synchronizing signals, means to transmit the remotely produced signals to the local position, means to receive the transmitted signals at the local position and means to transmit at the local position simultaneously both the locally generated synchronizing signals and the received remotely produced signals.

6. The method of television transmission which

- comprises the steps of generating at a local position synchronizing signals, remotely producing signals representative of an image to be transmitted, synchronizing the remotely produced signals by the locally generated synchronizing signals, transmitting the remotely produced signals to the local position, receiving the transmitted signals continuously transmitting the synchronizing signals from the local position, and transmitting signals representative of the received remotely produced signals simultaneously with the locally generated synchronizing signals from the local position under the control of the remotely produced signals.
7. A television system comprising a main transmitter, means for transmitting synchronizing energy continuously from said transmitter, an auxiliary transmitter, means to receive the transmitted synchronizing energy at the auxiliary transmitter, means to synchronize the auxiliary transmitter by the received synchronizing energy, means to transmit signals representative of an image to be transmitted from the auxiliary transmitter to the main transmitter, and means to retransmit from the main transmitter the transmitter signals from the auxiliary transmitter.
8. A television system comprising a main transmitter, means to modulate the transmitter by synchronizing signals, an auxiliary television transmitter, means to receive synchronizing signals from the main transmitter, means to isolate the received synchronizing signals, means to utilize the isolated synchronizing signals for synchronizing the auxiliary transmitter, means to

receive the signals transmitted from the auxiliary transmitter at the main transmitter, and means to retransmit the received signals from the main transmitter.

9. A television system comprising a main transmitter, means for transmitting synchronizing energy from said transmitter, an auxiliary transmitter, means at the auxiliary transmitter to receive the transmitted synchronizing energy, means to synchronize the auxiliary transmitter by the received synchronizing energy, means to transmit signals representative of an image to be transmitted from the auxiliary transmitter to the main transmitter, means to receive the signals transmitted from the auxiliary transmitter at the main transmitter, and means to retransmit the received signals from the main transmitter.

10. In a television system wherein is provided a main transmitter, and an auxiliary transmitter remote therefrom, the method of transmitting electro-optical representations of a scene from the main transmitter, which comprises the steps of transmitting synchronizing energy from the main transmitter, receiving the synchronizing energy at the auxiliary transmitter, synchronizing the auxiliary transmitter by the received synchronizing energy, transmitting energy representative of the object to be transmitted from the auxiliary transmitter to the main transmitter, receiving the transmitted energy from the auxiliary transmitter at the main transmitter, and retransmitting from the main transmitter the received signals.
